UNITED STATES PATENT OFFICE.

OSCAR V. PAYNE, OF CLEVELAND, OHIO, ASSIGNOR TO AUTO ORDNANCE CORPORATION OF NEW YORK, N. Y., A CORPORATION OF NEW YORK.

GUN-MAGAZINE.

1,358,105.

Specification of Letters Patent.

Patented Nov. 9, 1920.

Application filed July 27, 1920. Serial No. 399,283.

To all whom it may concern:

Be it known that I, OSCAR V. PAYNE, citizen of the United States of America, and resident of Cleveland, in the county of 5 Cuyahoga and State of Ohio, have invented new and useful Improvements in Gun-Magazines, of which the following is a specification.

This invention relates to a new and improved magazine for firearms and more specifically to a magazine of the box type adapted to be detachably connected to firearms whether of the full or semi-automatic or the manually operated types, this application being in part a division of my prior application Sr. No. 318,202, filed August 18, 1919.

It is an object of the present invention to provide a new and improved magazine which is composed of but few and simple members which may readily be placed in rigid association and positively connected by means which are integral parts of the members. It is an object to provide a magazine which may be rapidly assembled or dismantled. It is another object to provide readily operable means for connecting the magazine to a gun. It is a further object to provide a magazine which is reinforced by duplication of body thickness at points of stress and which is substantially rigid in construction. It is also an object to provide in connection with such a magazine, lips adjacent the delivery opening of the magazine which are adapted to properly guide the cartridges as they leave the magazine. Other and further objects will appear as the description proceeds.

I have illustrated certain preferred embodiments of my invention in association with the gun of my copending application above referred to, in the accompanying drawings in which—

Figure 1 is a fragmentary longitudinal section of the gun showing the magazine in position therein;

Fig. 2 is a section on line 2—2 of Fig. 1;

Fig. 3 is a side view, partly broken away showing the magazine on an enlarged scale;

Fig. 4 is a rear view of Fig. 3;

Fig. 5 is a section on line 5—5 of Fig. 3;

Fig. 6 is a section on line 6—6 of Fig. 3;

Fig. 7 is a fragmentary side view of the lower portion of the magazine;

Fig. 8 is a section on line 8—8 of Fig. 7; 55

Fig. 9 is a section on line 9—9 of Fig. 7;

Fig. 10 is a perspective view of a modified form of the magazine;

Fig. 11 is a view similar to the upper portion of Fig. 10, but showing a cartridge in 60 the magazine;

Fig. 12 is a vertical longitudinal section of the magazine shown in Fig. 10;

Fig. 13 is a section on line 13—13 of Fig. 12; and 65

Fig. 14 is a section on line 14—14 of Fig. 12.

In the embodiment shown in Figs. 1 to 9, the magazine is composed of the outer member 15, and the inner member 16 which is 70 telescoped longitudinally within the outer member from the top. The members are preferably formed of pressed metal. The outer member 15 is provided with the left-hand side wall 17, the front wall 18 which 75 extends around for a short distance onto the right side, the rear wall 19 which similarly extends a short distance onto the right side, and the right wall 20 which extends upward only a short distance from the bottom. The bottom of the member 15 is partly closed by the flange 21 extending inwardly from the left wall. The inner member 16 is provided with the right wall 22, the forward wall 23, the rear wall 24 and the bottom 25, and is of such dimension as to make a close sliding fit within the outer member. 80

As clearly shown in Figs. 3 and 5 the upper portions of the members 15 and 16 are provided with the resilient cartridge 90 releasing flanges or lips 26 and 27. These two flanges are identical and as shown in Fig. 3, the rear portion of the flange is cut off obliquely at 28 and the flange is extended in effective height by the cuts 29 and 30 95 which thus add to its resilience.

The lower portion of the wall 17 of the member 15 is provided with the spring catch 31 which catches above the bottom 25 of the member 16 and thus retains the two 100 members together, as best shown in Fig. 9.

The sides 17 and 22 have portions partially cut out to form the spring fingers 32 and 33. The lower portions of these spring fingers are sprung outwardly somewhat 105 from the magazine body and the upper portions 34 and 35 respectively are inclined inwardly, the circular openings 36 and 37

being provided at the junction of the two portions.

The magazine contains the spring 38 and the follower 39 which is provided with depending sides in sliding contact with the sides of the magazine.

The form of the device shown in Figs. 10 to 14 is generally similar to that just described. It comprises the outer member 10 which has the left side portion 41, the forward portion 42, and the rear portion 43, both of which extend a short distance onto the right side, and the bottom flange 44. The inner member comprises the right side portion 45, forward portion 46, rear portion 47 and bottom flange 48.

The side 41 is provided with the spring catch 49 which catches above the bottom flange 48 and thus retains the inner and outer members together. The rear portion 43 of the outer member is transversely recessed at 50 to receive a catch (not shown) to retain the magazine in the gun to which it is attached.

25 The magazine contains the spring 51 and follower 52 which latter has depending side portions in sliding contact with the side walls of the magazine. The side walls are perforated at 53 to permit inspection to determine the number of cartridges it contains.

The upper portions of the sides of the magazine are cut away to form the curved lips 54 and 55 and the upwardly extended rear portions overhang the top of the magazine at 56 and 57.

In Figs. 1 and 2 the form of magazine of Figs. 1 to 9 is shown applied to a gun of the type disclosed in my copending application to which reference has been made. The gun as shown comprises the barrel 60, stock 61, receiver 62, guard 63 and bolt 64. The stock and guard are both cut through in the rear of the barrel to receive the magazine housing 65 which is fastened to the receiver by the screws 66.

The magazine is slipped upwardly into the housing 65, the studs 67 on the gun passing up the portions 34 and 35 of the magazine, and into the openings 36 and 37. The studs 67 thus hold the magazine in place. The magazine may be readily detached by pressing inwardly upon the members 32 and 33 sufficiently to disengage the studs 67.

As shown in Fig. 1, the bolt, when it passes forward, engages the topmost cartridge and as it is carried forward the cartridge base flange engages the oblique rear portions 28 of the lips 26 and 27 and thus is forced to rise into alignment with the bore of the barrel. The curved lips 54 and 55 of the form of magazine shown in Figs. 10 to 14 operate in a similar manner.

65 Either of the two specific forms of my im-

proved magazine which I have shown may be constructed of relatively inexpensive sheet metal stampings. No separate fastening devices are required and the two parts are interlocked upon being telescoped together. 70 The parts are so formed that the magazine is reinforced at the points of maximum stress. In both forms the lips at the top of the magazine are formed so that they coact with the base flanges of the cartridges 75 to cause them to rise as they are delivered.

I claim:

1. A magazine adapted to be attached to a gun, comprising two members telescoping together longitudinally to form an elongate 80 tubular container for cartridges, and integral retaining means adapted to retain the members together.

2. A magazine adapted to be attached to a gun comprising two side members telescoping together longitudinally to form an elongate tubular container for cartridges, and an integral connecting means upon one of said members adapted to coact with a portion of the other member to retain the 90 members together.

3. A magazine comprising two side members telescoping together longitudinally to form an elongate tubular container for cartridges, both said side members having 95 front and rear flanges whereby these portions of the magazine are formed of a double thickness of material.

4. A magazine adapted to be attached to a gun, comprising two members telescoping 10 together longitudinally to form an elongate tubular container for cartridges, and an integral, inwardly extending spring catch upon the outer member adapted to coact with a part of the inner member to retain 10 the members together.

5. A magazine adapted to be attached to a gun, comprising two members telescoping together longitudinally to form an elongate tubular container for cartridges, the outer 11 member having an inwardly extending bottom flange adapted to limit the movement of the inner member.

6. A magazine adapted to be attached to a gun, comprising two members telescoping 11 together longitudinally to form an elongate tubular container for cartridges, the outer member having an inwardly extending bottom flange, and the inner member having an inwardly extending bottom flange adapted 12 to coact therewith to limit the relative movement of the two members.

7. A magazine adapted to be attached to a gun, comprising two members telescoping together longitudinally to form an elongate 12 tubular container for cartridges, the outer member having an inwardly extending bottom flange, and the inner member having an inwardly extending bottom flange adapted to coact therewith to limit the relative 13

movement of the two members, and integral retaining means adapted to hold the two bottom flanges in engagement.

8. A magazine adapted to be attached to a gun, comprising two members telescoping together longitudinally to form an elongate tubular container for cartridges, the outer member having an inwardly extending bottom flange, and the inner member having an inwardly extending bottom flange adapted to coact therewith to limit the relative movement of the two members, and an inwardly extending spring catch upon the outer member adapted to permit the bottom flange of the inner member to pass by it when assembling the two members and then to retain the two bottom flanges together.

9. A magazine adapted to be attached to a gun, comprising two interfitting members, the members being similarly curved where-

by one member may be telescoped within the other member, the members having interengaging bottom flanges adapted to limit the telescoping movement, and means adapted to automatically engage the inner member and retain the two members in telescoped relation.

10. A magazine adapted to be attached to a gun, comprising two interfitting members, the members being similarly curved whereby one member may be telescoped within the other member, the members having interengaging bottom flanges adapted to limit the telescoping movement, and an integral spring catch upon the outer member adapted to maintain the bottom flange of the inner member in engagement with that of the outer member.

Signed by me at Cleveland, Ohio, this 40 twenty-first day of July, 1920.

OSCAR V. PAYNE.
